UNITED STATES PATENT OFFICE

159,250

DOLL

Leon R. Cohen, Springfield, and Douglas J. Beck,
East Longmeadow, Mass., assignors to Van-
guard Corporation, Springfield, Mass., a corpo-
ration

Application July 18, 1949, Serial No. 3,982

Term of patent 3½ years

(Cl. D34—4)

To all whom it may concern:

Be it known that we, Leon R. Cohen and Douglas J. Beck, citizens of the United States, residing at Springfield and East Longmeadow, respectively, in the county of Hampden and Commonwealth of Massachusetts, have invented a new, original, and ornamental Design for a Doll, of which the following is a specification, reference being had to the accompanying drawings, forming part hereof:

Fig. 1 is a front perspective view of a doll showing our new design;

Fig. 2 is a rear perspective view of the doll shown in Fig. 1; and

Fig. 3 is a top plan view of the doll shown in Figs. 1 and 2.

The essential features of our design reside in its portions shown in full lines.

We claim:

The ornamental design for a doll, as shown and described.

LEON R. COHEN.
DOUGLAS J. BECK.
